UNITED STATES PATENT OFFICE.

JOHN B. WALSH, OF PROVIDENCE, RHODE ISLAND.

SCHOOL-SLATE.

SPECIFICATION forming part of Letters Patent No. 277,387, dated May 8, 1883.

Application filed May 1, 1882. (No model.)

To all whom it may concern:

Be it known that I, JOHN B. WALSH, of the city and county of Providence, and State of Rhode Island, have invented a new and useful Improvement in School-Slates; and I hereby declare that the following is a full, clear, and exact description of the same, reference being had to the accompanying drawings, forming part of this specification.

10 This invention has reference to an improvement on what are known in the art as "noiseless school-slates;" and it consists in a cover for the frame of a slate, made of elastic material, as will be more fully set forth hereinafter.

15 The frames of school-slates have heretofore been covered with soft material secured to the frame, so that when handled in school it will not scratch the desk, and will not make any noise or sound when laid down or moved on 20 the desk. Such covering material has been usually firmly secured to the frame of the slate, and could not be readily removed from the same when the slate was broken or became otherwise injured.

25 The object of this invention is to so construct the covering material that the same may be readily removed from the slate and placed on the frame of another slate, and be as firmly held as if it were permanently secured 30 thereto.

Figure 1 is a view of a slate-frame covered with an elastic material which envelops the sides and the edge of the frame. Fig. 2 is a sectional view showing the cover made of a 35 yielding woven fabric placed over the frame. Fig. 3 is a sectional view showing the frame covered with a fabric provided with a cord at the inner edges of the cover.

In the drawings, A is the slate; B, the 40 frame; C, the cover, and d d the cords on the inner edges of the covering material.

I prefer to make the cover C of some elastic material—such as india-rubber, or a woven fabric in which india-rubber is interwoven—so that the cover can be turned over the frame 45 and will be securely held by the elasticity of the material. A knitted fabric may also be made of sufficient elasticity to receive the frame and be tightly held when drawn over the same, as shown in the drawings. The 50 cover may also be made of non-elastic material, and provided at one or both edges with elastic bands or cords d, which, when drawn over the frame, will hold the material tightly on the frame; or, in place of the elastic cords 55 d d, cords or tapes may be inserted at one or both edges into a draw-hem, and when the material is placed over the frame the tapes or cords may be tied so as to draw the inner edges and secure the covering. A cover of 60 either of these materials or construction may be readily removed from the slate and placed on a new slate, and may thus be used on a number of slates in succession.

I am aware that an elastic slate-frame consisting of an endless tube of vulcanized rubber slit upon its inner side is old, and I do not claim such a slate-frame nor a similarly-constructed cover for slate-frames.

Having thus described my invention, I claim 70 as new and desire to secure by Letters Patent—

The combination, with a slate-frame, of a removable cover consisting of an endless web of textile material provided at its edge with a tightening-cord, substantially as described.

JOHN B. WALSH.
